US00D824637S

(12) United States Design Patent (10) Patent No.: US D824,637 S
(45) Date of Patent:  Aug. 7, 2018

(54) GLOVE

(71) Applicants: Willy Chen, Chino, CA (US); Jeff Lu, Chino Hills, CA (US); Benson Tu, Chino Hills, CA (US)

(72) Inventors: Willy Chen, Chino, CA (US); Jeff Lu, Chino Hills, CA (US); Benson Tu, Chino Hills, CA (US)

() Term: 15 Years

(21) Appl. No.: 29/590,605

(22) Filed: Jan. 11, 2017

(51) LOC (11) Cl. 02-06

(52) U.S. Cl.

USPC D2/617; D2/621

(58) Field of Classification Search

USPC D2/610, 611, 616, 617, 619, 621, 623

CPC A41D 19/00

See application file for complete search history.
